Joseph R. Brown,
of Greeley, Colorado.

UNITED STATES PATENT OFFICE.

JOSEPH R. BROWN, OF WASHINGTON, DISTRICT OF COLUMBIA, ASSIGNOR TO THE BROWN BAG-FILLING MACHINE COMPANY, OF FITCHBURG, MASSACHUSETTS, A CORPORATION OF MASSACHUSETTS.

ASSEMBLING APPARATUS.

No. 877,900.

Specification of Letters Patent.

Patented Feb. 4, 1908.

Application filed April 27, 1907. Serial No. 370,703.

To all whom it may concern:

Be it known that I, JOSEPH R. BROWN, a citizen of the United States, and a resident of Washington, in the District of Columbia, 5 have invented an Improvement in Assembling Apparatus, of which the following description, in connection with the accompanying drawing, is a specification, like letters on the drawing representing like parts.

10 This invention has for its object the production of an apparatus for facilitating the assembling of a series of different articles into a single package, and is more particularly designed for use in the assembling of a 15 series of small sealed bags of different kinds of seed into a large envelop or bag; which is subsequently sealed.

The apparatus of this invention, while suitable for a variety of uses, is particularly 20 designed for use in connection with an apparatus such as shown and described in the patent to B. F. Brown, No. 752,373, granted February 16, 1904 for apparatus for fastening filled bags. The small sealed bags containing different varieties of seed or similar 25 articles are placed in a series of bins, one kind or variety in each bin, and then the desired number of sealed bags are taken by operatives and placed in a larger bag or envelop 30 so that each larger bag or envelop will contain an assorted variety of bags of seed, or other articles.

The present apparatus has for its object facilitating the work of assembling smaller 35 packages into larger ones whereby it may be accomplished with ease, rapidity and economy.

The drawings illustrate the preferred form 40 of the apparatus as designed for use in connection with the patent to B. F. Brown referred to.

In the drawings, Figure 1 is a perspective view of a portion of an apparatus embodying the invention; Fig. 2 is a cross-section of a 45 slightly different form of apparatus embodying the invention; Fig. 3 is a cross-section taken on the line $x-x$, of Fig. 1; Fig. 4 is a similar cross section of another form of apparatus embodying the invention. Fig. 5 is 50 a similar cross section of still another form of apparatus embodying the invention.

The supply bins for the articles to be assembled into the bag or package are indicated at A, and may be of any desired shape 55 or construction. Preferably they are con-

structed with sloping sides and with the bottom at such an elevation from the floor that the articles when fed from the bins will be presented at a level from which they may be easily taken by an operative in a sitting 60 position. These bins are supported by any suitable framework, such as illustrated at B, and are of suitable sizes suited to the relative quantities of the articles to be assembled. The bins may also be arranged so as 65 to be readily kept filled from the floor above.

In the drawings, each bin is shown as provided with a discharge opening C, and sliding door D therefor, on one side of the bin at the bottom, but it is obvious that the bins may 70 discharge at both sides when it is desired to duplicate the apparatus. One sliding door, as indicated at D', may be arranged to cover the two openings of adjacent bins, if desired.

An endless conveyer E is arranged along 75 side of, and parallel with, the discharge openings in the series of bins A. This conveyer may be of any suitable construction, and as herein shown it is constructed in the same way as the conveyer illustrated at F in the 80 aforesaid Patent No. 752,373. It comprises an endless belt supported by rolls F mounted on the framework B. The upper run of the conveyer is arranged at a suitable level for the operative and at a distance from the discharge openings of the supply bins sufficient 85 to allow for the distributing reservoirs, to be described. A series of distributing reservoirs, as they are herein termed, are located 90 between the bins A and the endless conveyer E and in such position that the articles or material contained in the bins will flow out through the discharge openings into the distributing reservoirs. In Figs. 1 3 and 5 of the drawings these distributing reservoirs 95 are shown as constituted by a trough G partitioned off by partitions H extending upwardly therefrom so as to present a distributing reservoir in front of each supply bin A below the level of the discharge opening and the level of the upper run of the conveyer.

In Fig. 2 of the drawing the distributing reservoirs are shown as constituted by a flat horizontal shelf G² extending out on the same level as the bottom of the supply bin 105 and the upper run of the conveyer and partitioned off by partitions H².

In Fig. 4 the distributing reservoirs are shown as constituted by an upwardly inclined shelf G³ extending out from the bot- 110

tom of the bin to a level above the upper run of the conveyer and partitioned off by partitions H^2 .

In the construction indicated in Fig. 5 the bottom of the supply bin is carried down 5 below the level of the discharge opening and on to the same level as the distributing reservoirs. In this construction the material contained in the bottom of the bin is made 10 to serve as a check upon the outward flow of the material through the discharge opening.

From these variant constructions, all of which embody the broad features of the invention, it will be seen that the essentials are 15 that the distributing reservoir, whatever may be its form, shall be located between the bin and the conveyer and in a position to receive the flow of the material from the discharge opening. The size of the distributing 20 reservoir, its position vertically with respect to the upper run of the conveyer, its shape, whether flat or trough like, and its width from the bin toward the conveyer all depend more or less upon the particular conditions such as the tendency of the material 25 or articles to flow more or less freely out from the discharge opening.

The distributing reservoirs enable a constant supply of the articles to be assembled 30 to be kept in front of each supply bin, close to the upper run of the endless conveyer, and readily accessible to the hand of the operative. The partitions or the side walls of these distributing reservoirs prevent the articles coming from one bin mixing with those coming from another. The distributing 35 reservoirs assure a sufficient quantity of the articles to be assembled in the desired position without danger of the articles getting on to the upper run of the conveyer and being 40 carried away before the operative has time to place them in the package or bag.

It will be seen that the distributing reservoirs lend a great degree of elasticity to the 45 apparatus and enable the operatives to work to the greatest advantage in the handling of the articles. The supply bins A are filled from time to time and whenever the amount in the distributing bins runs low the doors D 50 are raised, allowing more articles to feed into the distributing reservoirs.

In the operation of the apparatus one operative is usually provided for each discharge opening of the supply bins and sits in front 55 of the endless conveyer opposite the discharge opening. With the endless conveyer moving as indicated by the arrow, the operative at the extreme right (viewing the drawing) will take the article, such as a small 60 sealed bag of a certain variety of seed from the distributing reservoir in front of the right hand supply bin and place it in the open bag or package on the upper run of the conveyer E. The operative at the extreme right may 65 either himself have placed this open bag or

package on the upper run of the conveyer, or it may have previously been placed there by another operative. The open bag or package then travels in the direction of the arrow with the one article in it to the next operative 70 sitting in front of the next bin, who takes from the second distributing reservoir a second article, such as a small sealed bag of a different variety of seed and places it in the open bag or envelop along with the first article. The open bag or package then travels to the third operative, and so on, until as many articles are placed in the open bag or package as may be desired, when it is taken by the conveyer E preferably, to a suitable 80 apparatus for closing or fastening the package, such for example as indicated in the aforesaid Patent No. 752,373.

Having described my invention, what I claim as new and desire to secure by Letters 85 Patent, is:—

1. In an apparatus of the class described, a series of supply bins provided with discharge openings, a conveyer passing in front of said openings, a distributing reservoir between 90 said conveyer and the discharge openings and arranged to receive the discharge from said supply bins.

2. In an apparatus of the class described, a series of supply bins provided with discharge 95 openings, a conveyer passing in front of said openings, a discharge reservoir between said conveyer and the said discharge openings provided with a series of partitions extending upwardly therefrom whereby a series of distributing reservoirs are formed.

3. In an apparatus of the class described, a series of supply bins provided with discharge 105 openings above the bottom of the bins, a conveyer passing in front of said openings, a series of distributing reservoirs one for each supply bin located between said conveyer and the said discharge openings and on the same level as the bottoms of the supply of the supply bins and arranged to receive the 110 discharge from said bins.

4. In an apparatus of the class described, a series of supply bins provided with discharge 115 openings above the bottom of the bins, a conveyer passing in front of said openings, a series of distributing reservoirs one for each supply bin located between said conveyer and the said discharge openings and on the same level as the bottoms of the supply bins and below the level of said conveyer.

5. In an apparatus of the class described, a series of supply bins provided with discharge 125 openings above the bottom of the bins, a conveyer passing in front of said openings, a trough extending parallel with and between said conveyer and the said discharge openings and provided with a series of partitions extending upwardly therefrom to form a series of distributing reservoirs, one for each supply bin.

6. In an apparatus of the class described, a series of supply bins provided with discharge openings above the bottom of the bins, a conveyer passing in front of said openings, a trough extending parallel with and between said conveyer and the said discharge openings and provided with a series of partitions extending upwardly therefrom to form a series of distributing reservoirs, one for each 10 supply bin, the said trough being arranged

on the same level as the bottom of the supply bins and below the level of the said conveyer.

In testimony whereof, I have signed my name to this specification, in the presence of two subscribing witnesses.

Correction in Letters Patent No. 877,900.

It is hereby certified that in Letters Patent No. 877,900, granted February 4, 1908, upon the application of Joseph R. Brown, of Washington, District of Columbia, for an improvement in "Assembling Apparatus," an error appears in the printed specification requiring correction, as follows: In line 109, page 2, the words "of the supply" should be stricken out; and that the said Letters Patent should be read with this correction therein that the same may conform to the record of the case in the Patent Office.

Signed and sealed this 25th day of February, A. D., 1908.

C. C. BILLINGS,

Acting Commissioner of Patents.

6. In an apparatus of the class described, a series of supply bins provided with discharge openings above the bottom of the bins, a conveyer passing in front of said openings, a trough extending parallel with and between said conveyer and the said discharge openings and provided with a series of partitions extending upwardly therefrom to form a series of distributing reservoirs, one for each 10 supply bin, the said trough being arranged

on the same level as the bottom of the supply bins and below the level of the said conveyer.

In testimony whereof, I have signed my name to this specification, in the presence of two subscribing witnesses.
